CLAIM

The ornamental design of an escalator handrail housing, as shown and described.

DESCRIPTION

FIG. 1 is a perspective view of an escalator handrail housing showing our new design;

FIG. 2 is a right side perspective view thereof;

FIG. 3 is a left side perspective view thereof;

FIG. 4 is a front elevational view thereof;

FIG. 5 is a left side elevational view thereof;

FIG. 6 is a right side elevational view thereof;

FIG. 7 is a top plan view thereof;

FIG. 8 is a bottom plan view thereof; and

FIG. 9 is a rear elevational view thereof.

The broken line showing of the steps and the handrail is for illustrative purposes only and forms no part of the claimed design.
